ARTHUR W. SMITH, OF NEW YORK, N. Y., ASSIGNOR TO, YOST WRITING MACHINE COMPANY,
OF ILION, NEW YORK, A CORPORATION OF NEW YORK.

TYPE-WRITING MACHINE.

No. 860,834.

Specification of Letters Patent.

Patented July 23, 1907.

Application filed October 5, 1905. Serial No. 281,406.

To all whom it may concern.

Be it known that I, ARTHUR W. SMITH, a citizen of the United States, and a resident of the borough of Manhattan, city of New York, in the county of New York and State of New York, have invented certain new and useful Improvements in Type-Writing Machines, of which the following is a specification.

My invention relates to typewriting machines and more particularly to means for affording a connection 10 and disconnection between the line spacing wheel and platen for fractional line spacing.

Heretofore great difficulty has been encountered in providing efficient fractional line spacing mechanism. It must be understood, in order to appreciate some of 15 these difficulties, that the very finest adjustment is required between the line spacing wheel and platen and that there must be absolutely no accidental displacement of the parts from this adjustment when once effected, as a thousandth of an inch displacement of a 20 character out of a line of writing is quite perceptible in the printed matter.

In devices where differential gearing was employed between the line spacing wheel and platen, there was almost invariably a "back lash" or lost motion in the 25 gear connections which affected the results. Then again when frictional means were employed to connect the line spacing wheel and platen considerable power, say thirteen pounds in some devices, was necessary to maintain the connection and this power must be overcome 30 in releasing the device, rendering it difficult for the operator to actuate. Even with this power the friction devices were unreliable, as the line spacing wheel was often accidentally displaced relatively to the platen when the line spacing lever was violently 35 actuated, as for instance when the carriage was restored and a line-spacing movement of the platen effected at a single operation.

In devices which received a rotary movement of a finger wheel or controlling piece and which required 40 considerable power or pressure to effect an engagement or disengagement between the line spacing wheel and platen an accidental displacement between the parts was liable to be effected without the operator observing it and the work was apt to be ruined.

45 In devices which employ interlocking teeth to effect a clutching engagement between the line spacing wheel and platen, it is necessary to have teeth of considerable size in order to bring about an effective interlocking engagement between the parts and a relative adjustment between the line spacing wheel and platen, or a fractional spacing of the platen for a distance less than the distance between two teeth of the engaging members cannot be effected, and the usefulness of the device is restricted. The type will strike on predetermined

fixed lines on the platen instead of using the entire surface of the platen. 55

In any such construction heretofore devised, the teeth of the engaging members restricted the adjustment of fractional spacing of the platen. Furthermore, in this class of devices the platen was often accidentally 60 displaced from its adjusted position while an engagement was being effected and often the displacement occurred without the operator's knowledge. Thus, if the platen happens to be adjusted to a point where the crowns of the teeth on both engaging members come 65 into contact during the engagement of the parts, then the locking of the parts together will cause the platen to rotate until the teeth are brought into proper interlocking mesh and however slight the movement of the platen, it is sufficient to throw the work out of alignment and to render the written matter uneven and unsatisfactory. 70

From the foregoing it will be understood that in prior devices where positive or interlocking means were employed to connect the line spacing wheel and platen 75 the platen could not be adjusted to any point relatively to the line spacing wheel and connected to the wheel at the point of adjustment.

The object of my present invention is to overcome the above and other defects that have been encountered heretofore in fractional line spacing mechanism 80 and to provide a fractional line spacing device which will be efficient in operation under all conditions of its use. I have provided means whereby the platen may be turned to any position relative to the line space 85 wheel and whereby it may be positively locked exactly in that position.

To the above and other ends which will hereinafter appear, my invention consists of the features of construction, arrangements of parts and combinations of 90 devices to be hereinafter described and claimed.

In the accompanying drawings wherein like reference characters indicate corresponding parts in the various views, Figure 1 is a detail, central, longitudinal, sectional view of a platen and line spacing wheel showing my invention applied thereto. Fig. 2 is a like view of the same with parts broken away, the section being taken on a plane at right angles to that shown at Fig. 1. Fig. 3 is a detail end elevation looking towards the line spacing wheel and with the finger wheel 100 sectioned away. Fig. 4 is an enlarged detail sectional view of the carrier for one of the locking members to be hereinafter more fully described. Fig. 5 is an enlarged detail perspective view of one of the locking members. Fig. 6 is a like view of another of said locking members. Fig. 7 is an enlarged detail perspective view of the line spacing wheel. Fig. 8 is a fragmentary sectional view similar to that shown in Fig. 1, but with 105

the parts locked in the disengaged positions. Fig. 9 is a sectional view corresponding to Fig. 4 but showing a different disposition of the parts. Fig. 10 is a side elevation of the same. Fig. 11 is a view of the devices 5 shown in Figs. 9 and 10 as seen from the top of said figures. Fig. 12 is a detail perspective view of the platen head at the right-hand end of the platen. Fig. 13 is a detail transverse sectional view showing the locking members, the section being taken on the line 10 $x-x$ in Fig. 8 and looking in the direction of the arrow at said line. Fig. 14 is a detail, central, sectional view of the cap or member secured to the right-hand platen head. Figs. 15 and 16 are views similar to Figs. 1 and 13, respectively, but showing a different adjustment of 15 the parts.

The cylindrical platen 1 may be of any desired construction. The one here shown is similar to that ordinarily employed in the Yost machine. It is preferably provided at its left-hand end with a platen head 2 which is secured to a hollow wooden core 3 of the platen by headed wood screws 4 which project through openings in the platen head and the stems of which take into the end of the core. An outwardly projecting sleeve 5 on the platen head 2 bears at its end against 20 the platen frame 6 and receives a spindle 7 which projects from a fixedly connected finger wheel 8, said spindle extending through a bearing opening in the platen frame and into the sleeve 5. A conical pin 9 extends through openings in the sleeve 5 and spindle 7 and 25 locks the spindle 7 and platen head 2 together. 30

The stem of a headed bolt 10 projects through a central opening in the platen head 2 and its inner threaded end is received in a tapped opening in a nut 11, external threads on which are received in a tubular 35 bearing member 12 which constitutes a part of the platen head 13 at the other end of the platen and which is illustrated in detail in Fig. 12. Said right-hand platen head has a cylindrical part 13^a of a size to fit snugly in the hollow platen core 3, and also a flange 40 13^b that lies against the end of said core, against which it is firmly held by the rod 10. Pins 14 project from 45 said flange 13^b into holes in the end of the core 3 and prevent relative rotation of said core and the platen head. The sheath of the platen projects beyond the right-hand end of the core 3 and a metallic ring 15 is 50 seated within said projecting sheath and constitutes a bearing for the flange 13^b of the right-hand platen head, as shown in Fig. 2. This ring 15 is fixed to the platen and bears at its inner edge against the core 3 thereof and the outer edge of the ring constitutes a bearing for the inner side of a line spacing wheel 16. The line spacing wheel is in the nature of a ring, such as that shown in detail in Fig. 7, and the inner surface 55 thereof is received on the peripheral bearing edge 17 of a member 19 (shown in detail in Fig. 14) which is secured to the platen head by headed screws 20 (see Fig. 2), the stems of which pass through openings 19^a in the flange-like portion of the member 19 and are received in tapped openings in the outer end of the 60 platen head.

A circumferential flange 21 is formed on the member 19 and constitutes a shoulder against which the outer side of the line spacing wheel 16 is adapted to bear, the member 19 thus constituting a bearing for 65 the line spacing wheel to rotate upon and preventing

a movement of the line spacing wheel longitudinally of the platen in one direction, whereas the ring 15 constitutes a bearing that prevents the line spacing wheel from moving longitudinally of the platen in the opposite direction. The cap or member 19, being 70 rigidly secured to the platen head by the screws 20 connects the parts and maintains the line spacing wheel in place on the platen head though it allows the wheel to rotate thereon. The member 19 has a sleeve-like portion 22 which is tapped at 23 to receive a screw 75 23^a, the inner end of which is received within a hole in a hollow stem 24 seated at one end in the sleeve 22, so that the stem is connected to the platen head to rotate therewith.

The outer end of the hollow stem 24 has a finger 80 wheel 25 rigidly connected thereto. A plunger 26 is received within the hollow stem 24 and is adapted to move longitudinally therein and the inner end of this plunger is tapped to receive a headed screw 27, the head of which is adapted to bear against the inner end 85 of the hollow stem and prevent an endwise withdrawal of the plunger. The outer end of the plunger is provided with a finger piece or button 28 by which the plunger 26 may be pushed inward. In order to provide for locking the plunger in its inner position, said 90 plunger, adjacent to this finger piece, has a reduced portion 29 which is adapted to register with a laterally extending opening 30 in the finger wheel when the plunger is moved to the innermost position shown in Fig. 8. Seated within this opening or channel 30 is a 95 bearing sleeve 31 which is frictionally held in place in the opening. A spindle 32 extends through the sleeve 31 and is provided at its inner end with a locking head 33 that is larger than the opening in the sleeve 31 and cooperates with one end of it to prevent 100 the withdrawal of the spindle from the sleeve. The outer end of the sleeve has an enlarged bore that receives a coiled expansion spring 34 which surrounds the spindle and bears at its inner end against the sleeve and at its outer end against the enlarged head 105 or finger piece 35 of the locking member or device.

Normally the plunger 26 may be moved from the position shown in Fig. 1 to that illustrated in Fig. 8 and when finger pressure is released therefrom it will be restored to normal position shown in Fig. 1, as will 110 hereinafter more clearly appear. The plunger may, however, when desired be locked in its pushed in position, shown in Fig. 8, by the locking head 33. Thus, when the plunger is moved to the position shown in Fig. 8 and the finger piece 35 is depressed to move the 115 locking member 33 to the locking position shown in this figure and finger pressure on the plunger 26 is released, the pressure exerted by a spring 36, in the manner to be hereinafter described, will maintain the locking head in the locked position and will prevent the 120 restoration of the plunger 26 to its normal position. In order to accomplish this result it will be understood that the tension of the spring 36 is greater than the spring 34 and that the pressure exerted by the spring 36 through the plunger 26 binds the locking head 33 125 in the locked position, overcoming the power of the restoring spring 34. The line spacing wheel is provided with a series of circularly arranged crown teeth 37 which extend from the line spacing wheel towards the opposite end of the platen into the annular space 130

inclosed by the ring 15. The tips or crowns of these teeth are preferably beveled, whereas the sides or body portions of the teeth are substantially parallel. The notches between the teeth 37 are adapted to receive a clutch tooth 38 projecting from a clutch member 39, shown in detail in Fig. 5. Said member 39 has a semi-circular part 40 that fits loosely over a semi-cylindrical part 41 of a carrier 42 that is loosely mounted in the tubular portion 12 of the right-hand platen head. The left-hand end part 42^a of the carrier 42 is cylindrical and fits in the tube 12 with freedom to move longitudinally of said tube, and this part of said carrier has its end engaged by the spring 36, which presses the carrier toward the right. The right-hand part 41 of said carrier is semi-cylindrical, and its end engages the head of the screw 27, which is threaded into the spindle 26, so that when said spindle is pressed inward, the carrier is moved toward the left against the tension of the spring 36. The right-hand end of the platen head 13 has a transverse longitudinal slot 43 formed therein, which slot is cut through the flange 13^a, the cylinder 13^a, and back a short distance into the tube 12, the walls 43^a and 43^b (Fig. 12) of said slot being plane parallel surfaces, each parallel to the axis 25 of the platen. The semi-circular part 40 of the member 39 fits loosely over the semi-cylindrical part 41 of the carrier 42 and inside of the tube 12, so that said member has both a longitudinal and turning movement. Said member 39 has radially projecting therefrom on opposite sides of the axis of the platen, two wings 39^a (Figs. 5 and 13), and the tooth 38 is in the nature of an extension of one of these wings. The wings 39^a project into the slot 43, the walls of which limit the turning movement of the member 39 in both directions. As shown in Fig. 8, the core 3 of the platen is cut away to admit the tooth 38. The wings 39^a are beveled on one side to form wedge surfaces 44 and 44^a respectively. The motion of the member 39 longitudinally of the platen is derived from the carrier 42. The semi-circular part 40 of said member has formed in its right-hand edge a V-shaped notch 45 that is adapted to be engaged by a pin 46 projecting radially from the carrier 42 near the right hand end thereof, when said carrier is moved inward by the spindle 26. When said pin engages said notch it serves to center the member 39 on the carrier. Said member is moved toward the right to press the tooth 38 into one of the notches between the teeth 37 of the line space wheel by spring pressure. Thus a plunger 47 (Fig. 9) is seated in a longitudinal bore 48 in the carrier 42, and a pin 49 projects from said plunger through a longitudinal slot 50 in the reduced, semi-cylindrical part 41 of said carrier, in position to engage the left-hand edge of the member 39. A spring 51 is seated in the bore 48 and compressed between the plunger 47 and a screw 52 threaded into said bore 48. The tension of said spring may be regulated by adjusting said screw. The tension on the spring 51 is much less than on the spring 36. The flattened portion 53 of the semi-cylindrical part 41 of the carrier 42 has a tapped opening 54 (Fig. 4) therein for coöperation with a headed screw 55 (Fig. 9) having a shouldered portion 56 that constitutes the pivot for a locking or clutch member 57 shown in detail in Fig. 6. The pivot for this locking member extends at right angles to the axis of the platen, as shown in Figs. 1 and 13, and the ends of the

locking member extend to opposite sides of its pivotal center and on opposite sides of the axis of the platen and are turned inwardly at right angles to the body portion thereof, as indicated at 58. The edge of each inwardly bent end is beveled or formed with a wedge-like face 59 or 59^a and these bevel faces are adapted to coöperate with the beveled faces 44 and 44^a respectively on the locking member 39. From an inspection of Fig. 13 it will be seen that the outer flat face 60 of the locking member 57 coöperates with the wall 43^b of the cut-out 43 in the right-hand platen head. The locking member 57, it will also be observed, is adapted to partake of the bodily movement of its carrier 42 longitudinally of the platen and is likewise adapted to receive an independent turning movement on its pivot 55, the surface 60 sliding against the surface 43^b. The engagement of these two surfaces prevents the member 57 and the carrier 42 from turning in the tube 12.

In the normal disposition of the parts shown in Figs. 1, 2, 13, 15 and 16, the line spacing wheel is positively locked to rotate with the platen. Figs. 1, 2 and 13 show the position the parts assume if one of the notches between two teeth 37 happens to be positioned centrally of the slot 43, while Figs. 15 and 16 show the position they assume if said notch happens to be to one side of the center of said slot 43. In either case, in the normal position of the parts, the carrier 42 and the clutch member 39 are both in their extreme right-hand positions, the tooth 38 being seated in the notch between two of the teeth 37, so that the member 39 is positively locked to said line space wheel. The locking member 57 has its wedge surfaces 59 and 59^a pressed into engagement with the wedge surfaces 44 and 44^a of the clutch member 39, by the tension of the spring 36. Said member 57 is thus wedged in between said member 39 on the one hand and the flat face 43^b of the slot 43 on the other, thus pressing the semi-circular part 40 of said member 39 against the opposite side of the tube 12. The wedge 59, engaging the wedge 44, prevents the platen from turning toward the back of the machine, and the wedge 59^a engaging the wedge 44^a, prevents rotation of the platen in the opposite direction. The platen head is thus positively locked to the member 39, which, in turn, is positively locked to the line space wheel. In this position of the parts, the pin 46 stands some little distance to the right of the notch 45 in the member 39.

Should the operator desire to release the platen from the line spacing wheel in order to effect a fractional line spacing movement of the platen, it is merely necessary to press the finger piece 28 to the left, thus moving the carrier 42 in a like direction. The effect of the initial portion of the movement of the carrier 42 is to carry the locking member 57 out of interlocking and wedging engagement with the coöperating locking member 39. While this release is being effected the spring 51 expands and holds the locking member 57 at the right-hand limit of its movement with the tooth 38 thereon engaged between two teeth 37 on the line spacing wheel. This engagement between the tooth 38 and the teeth on the line spacing wheel continues until the carrier 42 has moved far enough to entirely disengage or throw the wedging device or locking member 57 out of coöperation with the wedging members on the locking device 39. When this disengagement has been effected, the pin 46 on the carrier 42 will come into en-

gagement with the locking member 39, as indicated in Fig. 11, and a further movement of the carrier 42 to the left will cause the locking member 39 to travel with it and the parts will be moved to the disengaged position shown in Fig. 8, with the tooth 38 out of engagement with the line space wheel, and the locking member 57 disengaged from the member 39. In this movement, the pin 46, engaging the notch 45, has centered the member 39, so that its wings 39^a are central of the slot 43, as shown in Fig. 13. The platen may then be rotated to any desired extent by either of its finger wheels 8 or 25 independently of the line spacing wheel.

Should the operator for any reason desire to maintain the parts in the released positions, it is merely necessary to press the finger piece 35 in, thus forcing the locking head 33 at the other end of the spindle into the reduced portion 29 of the plunger 26, and while pressure is still maintained on the finger piece 35 pressure may be released from the finger piece 28 controlling the plunger. The effect of this is to place the pressure of the spring 36 on the plunger 26, thus forcing the shoulder 29^a on the plunger against the locking head 33 and preventing the spring 34 from restoring the locking head to its normal position as heretofore described.

When the operator desires to restore the parts to locking engagement again, it is merely necessary to press on the finger piece 28 which will free the locking head 33 from the pressure of the spring 36 and the locking head will be moved back to its normal position, thus releasing the plunger 26 and enabling all the parts to be restored to their normal positions. In the first part of the movements of the parts back to normal position, the carrier 42 and the locking members 39 and 57 carried thereby travel in unison until the tooth 38 engages between two teeth 37 on the line spacing wheel. In this movement the member 39 is free from the locking member 57, so that it is free to turn. The beveled tooth 38, therefore, is guided by the beveled teeth 37, and readily enters the notch between them, turning slightly one way or the other, if necessary. When the tooth 38 is firmly seated in place between the teeth 37, as indicated in Fig. 7, then the movement of the locking member 39 to the right will be arrested, but a further continued movement of the carrier 42 takes place and during the movement of the carrier 42 independently of the locking member 39 the spring 51 is compressed, it being understood that the tension of the spring 36 is much greater than that of the spring 51. This continued movement of the carrier towards the normal position will impart a bodily movement to the locking member 57 which is carried thereby, and will force the inclined wedging faces 59 and 59^a thereof into a wedging engagement with the inclined faces 44 and 44^a on the locking member 39, and when the parts are in effective wedging and interlocking engagement the carrier will be arrested from further movement and the platen will be effectively and positively locked to the line spacing wheel at the exact point where the platen was adjusted relatively to the wheel.

During the engaging movement of the locking member 39, hereinbefore described, the tooth 38 thereon is brought into engagement with the teeth 37 on the line spacing wheel when the locking member 39 is free to receive a limited turning movement on its bearings and around the axial center of the platen.

If during the engagement of these parts the beveled crown of the tooth 38 should meet the beveled crown of a tooth 37 on the line spacing wheel, the locking member 39 will be turned on its bearings around the axis of the platen until the tooth 38 finds its proper position between the two teeth of the line spacing wheel, as shown in Fig. 16, it being understood that the line spacing wheel is at this time maintained against accidental displacement by a spring roller detent 61 (Fig. 3). After the tooth 38 has been properly centered and has its parallel sides received between the parallel sides of two adjacent teeth 37 on the line spacing wheel and has reached the limit of its engaging movement, then the movement of the carrier 42 will, as heretofore pointed out, be continued. Any change in the angular position of the engaging member 39 effected during its engagement with the line spacing wheel will displace the wings 39^a on the locking member, so that they assume different angular positions in the cut-out portions 43 of the platen head. During the bodily movement of the locking member 57 with the carrier one or the other of the inclined faces 59 and 59^a will be brought into engagement with its coöperating inclined face 44 or 44^a before the other, and a further bodily movement of the locking member 57 with its carrier effects a turning of the locking member 57 on its pivot, so as to automatically swing the member 57 to a position where both of its wedge faces 59 and 59^a are in engagement with the corresponding faces 44 and 44^a, so that it will properly coöperate with the locking member 39 in the angular position it has assumed during the engagement of this member with the line spacing wheel.

In Figs. 1, 2 and 13 of the drawings I have illustrated the locking member 39 as being centered with in the opening 43 in the platen head, and in these circumstances the locking member 57 will move to its locking position, shown in Fig. 1, without turning on its pivotal center, both engaging surfaces 59 and 59^a on the locking member 57 simultaneously engaging their respective coöperating wedging surfaces 44 and 44^a on the locking member 39. But in Figs. 15 and 16, said member 39 is displaced and the member 57 is correspondingly inclined.

From the foregoing it will be understood that the single tooth 38 is employed to interlock with and engage the large teeth 37 on the line spacing wheel and that during this engagement the locking member 39 may receive automatically a rotation around the longitudinal axis of the platen, and that during the engagement of the locking member 57 with the wedging surfaces on the locking member 39 said locking member 57 may automatically turn on its pivot to effect adjustment of the locking member 39, and thus the parts automatically regulate themselves or compensate for any shifting of the parts which may be effected by the engagement between the locking member 39 and the line spacing wheel, and none of the shifting thus automatically effected displaces the platen relatively to the line spacing wheel so that the platen may be positively secured to the line spacing wheel at any point in the adjustment of the former relatively to the latter.

It will also be observed that I have provided disengageable wedge-like clutch members that are pro-

vided with hand-actuated means for moving said clutch or locking members towards and away from each other; that one of these members 39 is, or may be, operatively connected to the line spacing wheel, whereas 5 another locking or clutch member 57 is operatively connected to the platen; that the movement of these members towards and away from each other effects a locking and disengagement between the line spacing wheel and platen; that one of the members 57 has a 10 bodily reciprocating movement with the carrier 42 and an independent pivotal movement around its pivot 55; that the member 39 has a bodily reciprocating movement towards and away from the teeth 37 of the line spacing wheel and that this movement is independent 15 of but in the direction of the engaging and disengaging movement of the member 57; that the interlocking clutching members when brought into engagement automatically adjust the clutching means to the relative adjustment effected between the platen and the 20 line spacing wheel and that the spring 36 maintains the two locking members in clutching engagement and also maintains the locking member 39 in clutching and interlocking engagement with the line spacing wheel.

25 I do not wish to be understood as limiting my invention to the features of construction herein shown and described since I believe I am the first to provide disengageable interlocking clutch members which are effective to positively lock the line spacing wheel and platen at any point in the relative adjustment of the 30 two. There are likewise many features of the invention which I regard as broadly novel, such, for instance, as the means for affording an automatic adjustment of the interlocking clutching means to the relative adjustment effected between the line spacing wheel and platen.

While I have shown and described the clutch mechanism for connecting a line spacing wheel and platen, for which such clutch mechanism is particularly adapted, nevertheless, it should be understood that I do not limit the use of the clutch mechanism to the particular relation shown as it may be employed in various machines to effect a connection between two parts that have a relative adjustment and in which it is essential 45 that a nice adjustment be effected and maintained and a rigid connection provided.

When I refer herein and in the accompanying claims to means for "positively connecting the line spacing wheel and platen", I mean to designate means for rigidly connecting the parts as by effecting an interlocking connection between them as distinguished from a mere frictional connection, and when I refer to means for connecting the platen and line spacing wheel "at any point in the relative adjustment between the 50 two", I mean to include means for connecting the line spacing wheel and platen to rotate together, such means being effective to connect these parts together at any point where the parts can be located by a relative rotary adjustment between them and without affecting 55 that adjustment as distinguished from devices, for instance, having engaging teeth that may be thrown into or out of engagement, but in which an adjustment finer than the teeth employed to connect the clutch members cannot be effected.

What I claim as new and desire to secure by Letters 65 Patent, is:-

1. In a typewriting machine, the combination of a line spacing wheel, a platen that is adapted to be turned relatively to said wheel, and disengageable interlocking means for positively connecting the platen and line spacing wheel 70 at any point in the relative adjustment between the two.

2. In a typewriting machine, the combination of a line spacing wheel, a platen that is adapted to be turned relatively to said wheel, and disengageable interlocking clutch members for positively connecting the platen and line 75 spacing wheel at any point in the relative adjustment between the two.

3. In a typewriting machine, the combination of a line spacing wheel, a platen that is adapted to move relatively to said line spacing wheel, and interlocking means for 80 positively connecting said line spacing wheel and platen at any point in the relative adjustment between the two, said connecting means comprising a locking member operatively connected to one of said parts and having an inclined engaging face, a coöperating locking member operatively connected to the other of said parts and having an inclined engaging face, and hand actuated means for moving said locking members towards and away from each other. 85

4. In a typewriting machine, the combination of a line spacing wheel, a platen that is adapted to turn independently thereof, a wedge-like locking member operatively connected to one of said parts, a coöperating pivoted wedge-like locking member operatively connected to the other of said parts, and means for effecting a relative movement of the locking members towards and away from each other 90 to effect a positive interlocking connection and disconnection between the line spacing wheel and platen at any point in the relative adjustment between the two.

5. In a typewriting machine, the combination of a line spacing wheel, a platen that is adapted to turn independently thereof, a wedge-like locking member operatively connected to one of said parts, a second coöperating wedge-like locking member operatively connected to the other of said parts, and mounted to have a bodily reciprocating movement and an independent pivotal movement, and hand actuated means for effecting the bodily movement of said second locking member towards and away from the other locking member to effect a positive interlocking connection and disconnection between the line spacing wheel and platen at any point in the relative adjustment between the 100 two. 105

6. In a typewriting machine, the combination of a line spacing wheel, a platen that is adapted to turn independently thereof, a hand actuated reciprocating carrier operatively connected to one of said parts, a locking member pivoted to said reciprocating carrier so as to have a bodily movement with the carrier and an independent pivotal movement thereon, and a second coöperating locking member operatively connected to the other of said platen and line spacing wheel parts and with which said first mentioned locking member coöperates to lock the line spacing wheel and platen together. 110

7. In a typewriting machine, the combination of a line spacing wheel, a platen that is adapted to turn independently thereof, a hand actuated reciprocating carrier operatively connected to one of said parts, a locking member pivoted to said reciprocating carrier so as to have a bodily movement with the carrier, and an independent pivotal movement thereon, and a second coöperating locking member, means for affording a positive clutching engagement 120 and disengagement between said locking member and the other of said platen and line spacing wheel parts, and whereby the line spacing wheel and platen may be positively locked together or may receive a relative adjustment. 125

8. The combination of two parts that are adapted to receive a relative adjustment, and means for connecting said parts together, said connecting means comprising a pivoted wedging device, coöperating interlocking means, and means for effecting a relative movement between said pivoted wedging device and the coöperating interlocking means, whereby an interlocking positive connection can be effected or broken at will. 130 135 140

9. The combination of two parts that are adapted to receive a relative adjustment, and means for connecting said parts together, said connecting means comprising a pivoted wedging device operatively connected to one of said parts, co-operating interlocking means operatively connected to the other of said parts, and means for effecting a relative movement between said pivoted wedging device and the co-operating means, whereby an interlocking positive connection can be effected or broken at will. 85
10. 10. The combination of two parts that are adapted to receive a relative adjustment, and means for connecting said parts together, said connecting means comprising two members that are adapted to be moved towards and away from each other and to interlock with each other to positively connect said parts together, one of said interlocking members having an inclined engaging face, and means for affording an independent movement of one of said members in substantially the direction of its engaging movement. 90
11. The combination of two relatively adjustable parts, and interlocking clutching means for positively connecting said parts in any adjusted position thereof, said clutching means including means for automatically adjusting the clutching means to the adjustment between said relatively adjustable parts. 100
12. The combination of two relatively adjustable parts, interlocking clutching means for positively connecting said parts in the adjusted position thereof, and means for affording an automatic adjustment of the clutching means to the adjustment between said parts when the clutching means are brought into interlocking clutching engagement. 105
13. The combination of two relatively adjustable parts, and interlocking clutching means for positively connecting said parts in the adjusted position thereof; said clutching means including a pivoted device which is brought into a wedging and interlocking engagement on opposite sides of its pivot, to automatically adjust the clutching means to the adjustment between said relatively adjustable parts. 110
14. In a typewriting machine, the combination of a line spacing wheel, a platen that is adapted to be adjusted relatively thereto, and interlocking clutching means for positively connecting the line spacing wheel and platen, said clutching means including means for automatically adjusting the clutching means to the relative adjustment of the line spacing wheel and platen. 115
15. In a typewriting machine, the combination of a line spacing wheel, a platen that is adapted to be adjusted relatively thereto, interlocking clutching means for positively connecting the line spacing wheel and platen, and means for affording an adjustment of the clutching means to the relative adjustment between the line spacing wheel and platen when the clutching means are brought into interlocking clutching engagement. 120
16. In a typewriting machine, the combination of a line spacing wheel, a platen that is adapted to be adjusted relatively thereto and interlocking clutching means for positively connecting the line spacing wheel and platen, said clutching means including a pivoted device which is brought into a wedging and interlocking engagement on opposite sides of its pivot to automatically adjust the clutching means to the relative adjustment of the line spacing wheel and platen. 125
17. In a typewriting machine, the combination of a line spacing wheel, a platen that is adapted to be adjusted relatively thereto, interlocking clutching means for positively connecting the line spacing wheel and platen, said clutching means including a pivoted device which is brought into a wedging and interlocking engagement on opposite sides of its pivot to automatically adjust the clutching means to the relative adjustment of the line spacing wheel and platen, and hand controlled means for effecting a movement of said pivoted device into and out of wedging and interlocking engagement, such movement being independent of the pivotal movement of said device. 130
18. In a typewriting machine, the combination of a line spacing wheel, a platen that is adapted to be adjusted relatively thereto, interlocking clutching means for positively connecting the line spacing wheel and platen, said clutching means including means for automatically adjusting the clutching means to the relative adjustment of the line spacing wheel and platen, and hand actuated means for effecting an engagement and disengagement of the interlocking clutching means. 135
19. In a typewriting machine, the combination of a line spacing wheel, a platen that is adapted to be adjusted relatively thereto, interlocking clutching means for positively connecting the line spacing wheel and platen, means for affording an automatic adjustment of the clutching means to the relative adjustment between the line spacing wheel and platen when the clutching means are brought into interlocking clutching engagement, and independent hand controlled means for effecting an engagement and disengagement of the interlocking clutching means. 140
20. In a typewriting machine, the combination of a line spacing wheel, a platen that is adapted to rotate independently of said wheel, and interlocking clutching means for positively connecting the line spacing wheel and platen, said clutching means comprising two clutching members one operatively connected to the platen and the other operatively connected to the line spacing wheel and one of said members having a bodily movement towards and away from the other member and into and out of engagement therewith, a finger piece operatively connected to the movable member to effect the movement specified, and means for affording an automatic independent movement of said movable member to enable it to automatically adjust itself to the relative adjustment between the line spacing wheel and platen when the clutch members are brought into interlocking engagement. 145
21. In a typewriting machine, the combination of a line spacing wheel, a platen that is adapted to rotate independently of said wheel, and interlocking clutching means for positively connecting the line spacing wheel and platen, said clutching means comprising two clutching members one operatively connected to the platen and the other operatively connected to the line spacing wheel and one of said members having a wedging engagement with the other and being movable in two directions. 150
22. In a typewriting machine, the combination of a line spacing wheel, a platen that is adapted to rotate independently of said wheel, and interlocking clutching means for positively connecting the line spacing wheel and platen, said clutching means comprising two clutching members one operatively connected to the platen and the other operatively connected to the line spacing wheel and one of said members being pivoted and adapted for wedging and interlocking engagement on opposite sides of its pivot, and means for moving one of said members relatively to the other into and out of clutching engagement. 155
23. In a typewriting machine, the combination of a line spacing wheel, a platen that is adapted to rotate independently of said wheel, and interlocking clutching means for positively connecting the line spacing wheel and platen, said clutching means comprising two clutching members one fixed to rotate with the platen but pivoted to turn on an axis at substantially right angles to the axis of the platen, and the other adapted to be fixed to rotate with the line spacing wheel, and means for bringing said members into an interlocking and wedging engagement to cause them to rotate together. 160
24. The combination of two relatively adjustable parts, interlocking clutching means for positively connecting said parts in the adjusted position thereof, said clutching means including means for automatically adjusting the clutching means to the adjustment between said relatively adjustable parts, and a spring for maintaining the clutching means in engagement. 165
25. The combination of two relatively adjustable parts, interlocking clutching means for positively connecting said parts in the adjusted position thereof, means for affording an automatic adjustment of the clutching means to the adjustment between said parts when the clutching means are brought into interlocking clutching engagement, a spring for maintaining the clutching means in engagement, and means for locking the clutching means disengaged. 170
26. The combination of two relatively adjustable parts, interlocking clutching means for positively connecting said parts in the adjusted position thereof, said clutching means including a pivoted device which is brought into a wedging and interlocking engagement on opposite sides of its pivot to automatically adjust the clutching means to the adjustment between said relatively adjustable parts. 175

- spring for maintaining the clutching means in engagement, and means for locking the clutching means disengaged.
27. In a typewriting machine, the combination of a line spacing wheel, a platen that is adapted to be adjusted relatively thereto, interlocking clutching means for positively connecting the line spacing wheel and platen, said clutching means including means for automatically adjusting the clutching means to the relative adjustment of the line spacing wheel and platen, and a spring for maintaining the clutching means in engagement. 5
28. In a typewriting machine, the combination of a line spacing wheel, a platen that is adapted to be adjusted relatively thereto, interlocking clutching means for positively connecting the line spacing wheel and platen, means for affording an automatic adjustment of the clutching means to the relative adjustment between the line spacing wheel and platen when the clutching means are brought into interlocking clutching engagement, a spring for maintaining the clutching means in engagement, and means for locking the clutching means disengaged. 10
29. In a typewriting machine, the combination of a line spacing wheel, a platen that is adapted to be adjusted relatively thereto, interlocking clutching means for positively connecting the line spacing wheel and platen, said clutching means including a pivoted device which is brought into wedging and interlocking engagement on opposite sides of its pivot to automatically adjust the clutching means to the relative adjustment of the line spacing wheel and platen, a spring for maintaining the clutching means in engagement, and means for locking the clutching means disengaged. 15
30. In a typewriting machine, the combination of a line spacing wheel, a platen adapted to turn independently of said wheel, clutch teeth on said wheel, a clutch member adapted to engage said teeth, and a second clutch member adapted to positively engage the first mentioned clutch member. 20
31. In a typewriting machine, the combination of a line spacing wheel, a platen adapted to turn independently of said wheel, clutch teeth on said wheel, a clutch member adapted to engage said teeth, and a second clutch member adapted to positively engage the first mentioned clutch member, the line spacing wheel and platen being positively locked to rotate together when the first mentioned clutch member engages the teeth on the wheel and the first mentioned clutch member is engaged by the second. 25
32. In a typewriting machine, the combination of a line spacing wheel, a platen adapted to turn independently of said wheel, clutch teeth on said wheel, a clutch member adapted to engage said teeth, a second clutch member adapted to positively engage the first mentioned clutch member, and hand actuated means for first separating said clutch members and for then separating the first mentioned clutch from engagement with the teeth on the line spacing wheel. 30
33. In a typewriting machine, the combination of a line spacing wheel, a platen adapted to turn independently of said wheel, clutch teeth on said wheel, a clutch member adapted to engage said teeth, a second clutch member adapted to positively engage the first mentioned clutch member, the line spacing wheel and platen being positively locked to rotate together when the first mentioned clutch member engages the teeth on the wheel and the first mentioned clutch member is engaged by the second, and hand actuated means for first separating said clutch members and for then separating the first mentioned clutch from engagement with the teeth on the line spacing wheel. 35
34. In a typewriting machine, the combination of a line spacing wheel, a platen adapted to turn independently of said wheel, clutch teeth on said wheel, a clutch member adapted to engage said teeth, and a second clutch member adapted to positively engage the first mentioned clutch member by an interlocking wedging engagement. 40
35. In a typewriting machine, the combination of a line spacing wheel, a platen that is adapted to rotate independently of said line spacing wheel, and interlocking clutching members for positively connecting the said wheel and platen and which members receive a relative movement 45 to effect a wedging engagement between them, one of said members being pivoted so that it may turn on its pivot during engagement between said members in order to automatically regulate itself to the adjustment between the platen and line spacing wheel.
36. In a typewriting machine, the combination of a line spacing wheel, a platen that is adapted to rotate independently of said line spacing wheel, a carrier that is movable longitudinally of the platen, a clutch member pivoted to said carrier, the pivotal axis of the carrier being at substantially right angles to the axis of the platen, a second 50 co-operating clutch member, wedging surfaces between said clutch members, and hand actuated means for effecting a relative movement of said clutch members longitudinally of the platen to afford an interlocking wedging engagement between the clutch members and thereby positively lock the platen to the line spacing wheel. 90
37. In a typewriting machine, the combination of a line spacing wheel, a platen that is adapted to rotate independently of said line spacing wheel, a carrier that is movable longitudinally of the platen, a clutch member pivoted to said carrier about centrally of the platen, the pivotal axis of the clutch member extending substantially at right angles to the axis of the platen, wedging surfaces on opposite sides of the pivotal center of said clutch member, and a co-operating clutch member with which said pivoted clutch member is adapted to interlock with a wedging action to positively connect the line spacing wheel and platen. 100
38. In a typewriting machine, the combination of a line spacing wheel, a platen that is adapted to rotate independently of said line spacing wheel, a carrier that is movable longitudinally of the platen, a spring for moving said carrier in one direction, hand operated means for moving the carrier in the opposite direction against the pressure of the spring, a clutch member pivoted to said carrier about centrally of the platen, the pivotal axis of the clutch member extending at substantially right angles to the axis of the platen, wedging surfaces on opposite sides of the pivotal center of said clutch member, and a co-operating clutch member with which said pivoted clutch member is adapted to interlock with a wedging action to positively connect the line spacing wheel and platen. 110
39. In a typewriting machine, the combination of a line spacing wheel, a platen that is adapted to rotate independently of said line spacing wheel, and clutch mechanism for positively connecting the line spacing wheel and platen, said clutching mechanism comprising two clutch members, the first being adapted to be thrown into and out of positive engagement with the line spacing wheel and the second being adapted to be thrown into and out of positive engagement with the first clutch member, so that an interlocking engagement may be effected between the two clutch members and between the line spacing wheel and platen. 115
40. In a typewriting machine, the combination of a line spacing wheel, a platen that is adapted to rotate independently of said line spacing wheel, a series of teeth on said wheel, a clutch member that is adapted to positively engage the said teeth to positively connect the clutch member to the wheel, a second clutch member adapted to interlock with and positively engage the first mentioned clutch member by a wedging action, and a spindle that is adapted to control the engagement and disengagement between the clutch members and to control the engagement and disengagement between one of said clutch members and the teeth on the line spacing wheel. 120
41. In a typewriting machine, the combination of a line spacing wheel, a platen that is adapted to rotate independently of said line spacing wheel, a series of teeth on said wheel, a clutch member that is adapted to positively engage the said teeth to positively connect the clutch member to the wheel, a second clutch member adapted to interlock with and positively engage the first mentioned clutch member by a wedging action to positively lock the line spacing wheel and platen to rotate together, a spring restored spindle that is adapted to control the engagement and disengagement between the clutch members and to control the engagement and disengagement between one of said clutch members and the teeth on the line spacing wheel, and means for locking said spindle against the spring pressure thereon. 125
- 80

42. In a typewriting machine, the combination of a line spacing wheel, a platen that is adapted to rotate independently of said line spacing wheel, a clutch member that has a limited rotary movement independently of the platen and is adapted to positively engage the line spacing wheel, and a second clutch member connected to rotate with the platen and to be brought into positive interlocking engagement with the first mentioned clutch member. 85
43. In a typewriting machine, the combination of a line spacing wheel, a platen that is adapted to rotate independently of said line spacing wheel, a clutch member that has a limited rotary movement independently, and which is movable longitudinally of the platen to effect a positive interlocking engagement and disengagement between the line spacing wheel and platen, and a second clutch member connected to rotate with the platen and to be brought into positive interlocking engagement with the first mentioned clutch member. 90
44. In a typewriting machine, the combination of a line spacing wheel, a platen that is adapted to rotate independently of said line spacing wheel, and two interlocking clutch members for positively connecting the line spacing wheel and platen, both of said clutch members being adapted to move longitudinally of the platen in their movements into and out of interlocking engagement, one of said clutch members having a limited rotary movement independently of the platen and being adapted to positively engage the line spacing wheel, and the other clutch member being adapted to engage and interlock with the first mentioned clutch member in any position it may assume relatively to the platen. 100
45. In a typewriting machine, the combination of a line spacing wheel, a platen that is adapted to rotate independently of said line spacing wheel, two positively engageable clutch members, both connected to rotate with the platen and one of them having a limited rotary movement relatively to the platen and adapted to positively engage the line spacing wheel, and means for controlling the engagement between the said clutch members and between one of said clutch members and the line spacing wheel. 115
46. In a typewriting machine, the combination of a line spacing wheel, a platen that is adapted to rotate independently of said line spacing wheel, two positively engageable clutch members both connected to rotate with the platen and one of them having a limited rotary movement relatively to the platen and adapted to positively engage the line spacing wheel and the other being adapted to automatically accommodate itself to the relative adjustment between the other clutch member and the platen, and means for controlling the engagement between the said clutch members and between one of said clutch members and the line spacing wheel. 125
47. In a typewriting machine, the combination of a line spacing wheel, a platen that is adapted to rotate independently of said line spacing wheel, two positively engageable clutch members both connected to rotate with the platen and one of them having a limited rotary movement relatively to the platen and adapted to positively engage the line spacing wheel and the other clutch member having a pivotal movement and a wedging action in its co-operation with the other clutch member, and means for controlling the engagement between the said clutch members and between one of said clutch members and the line spacing wheel. 140
48. In a typewriting machine, the combination of a line spacing wheel, a platen that is adapted to rotate independently of said line spacing wheel, and two clutch members, one of which is movable longitudinally of the platen into and out of positive engagement with the line spacing wheel, and the other movable longitudinally of the platen into and out of positive engagement with its co-operating clutch member, said clutch members including means for automatically adjusting them to the relative adjustment between the line spacing wheel and platen. 150
49. In a typewriting machine, the combination of a line spacing wheel, a platen that is adapted to rotate independently of said line spacing wheel, two clutch members, one of which is movable longitudinally of the platen into and out of positive engagement with the line spacing wheel, 155
50. In a typewriting machine, the combination of a line spacing wheel, a platen that is adapted to rotate independently of said line spacing wheel, two clutch members, one being adapted to positively engage the line spacing wheel and having a pivotal movement on an axis which is coincident with the axis of the platen and the other clutch member being pivoted on an axis that extends transversely to the axis of the platen and has a wedging interlocking engagement with its co-operating clutch member. 100
51. In a typewriting machine, the combination of a line spacing wheel, a platen that is adapted to turn independently of said wheel, releasable clutching means for positively connecting said line spacing wheel and platen to turn together, said clutching means comprising two interlocking clutch members, one operatively connected to the platen and the other operatively connected to the line spacing wheel, one having a limited turning movement independently of the part that carries it and on an axis that extends longitudinally of the platen, and the other having a pivotal movement on the part that carries it and on an axis that extends at substantially right angles to the axis of the platen, and means for affording a further movement of one of said clutch members towards and away from the other and into and out of a wedging interlocking engagement. 110
52. In a typewriting machine, the combination of a line spacing wheel, a platen that is adapted to turn independently of said wheel, releasable clutching means for positively connecting said line spacing wheel and platen to turn together, said clutching means comprising two interlocking spring engaged clutch members one operatively connected to the platen and the other operatively connected to the line spacing wheel and one having a limited turning movement independently of the part that carries it, and on an axis that extends longitudinally of the platen, and the other having a pivotal movement on the part that carries it and on an axis that extends at substantially right angles to the axis of the platen, and means for affording a further movement of one of said clutch members towards and away from the other longitudinally of the platen and into and out of a wedging interlocking engagement, and means for locking one of the clutch members in the disengaged or released position. 120
53. In a typewriting machine, the combination of a line spacing wheel, a platen that is adapted to turn independently of said wheel, releasable clutching means for positively connecting said line spacing wheel and platen to turn together, said clutching means comprising two interlocking clutch members, one operatively connected to the platen and the other disengageably connected by positive locking means to the line spacing wheel and one having a limited turning movement independently of the part that carries it and on an axis that extends longitudinally of the platen, and the other having a pivotal movement on the part that carries it and on an axis that extends at substantially right angles to the axis of the platen, and means for affording a further movement of one of said clutch members towards and away from the other and into and out of a wedging interlocking engagement, and hand controlled means for controlling the disengagement and engagement between the two clutch members and between one of said members and the line spacing wheel. 135
- Signed at the borough of Manhattan, city of New York, in the county of New York and State of New York, this 3d day of October, A. D. 1905. 155
